UNITED STATES PATENT OFFICE.

OTTO DE CARDY, OF CHICAGO, ILLINOIS.

DESIGN FOR AN AUTOMOBILE SIDE LIGHT.

Application filed November 24, 1924. Serial No. 11,463. Term of patent 7 years.

To all whom it may concern:

Be it known that I, OTTO DE CARDY, a citizen of the United States, residing in Chicago, in the county of Cook and State of Illinois, have invented a new, original, and ornamental Design for Automobile Side Lights, of which the following is a specification, reference being had to the accompanying drawing, forming a part thereof.

Figures 1 and 2 are respectively side and plan views of my automobile side light showing my new design.

I claim:

The ornamental design for an automobile side light as shown.

OTTO DE CARDY.
